FIG. 3. 25 24 23

FIG. 1.

INVENTOR:

EUGENE STPIERRE,

~~By John G. Borchard~~

ATTY.

UNITED STATES PATENT OFFICE

2,550,880

KNITTED FABRIC

Eugene St. Pierre, Pawtucket, R. I., assignor to
Hemphill Company, Central Falls, R. I., a corporation of Massachusetts

Application March 20, 1948, Serial No. 16,023

1 Claim. (CL. 66—201)

1

This invention relates to a new and useful improvement in knitted fabric and methods of knitting on a circular, independent needle, knitting machine. It relates particularly to a method of binding the end of a yarn into the knitted fabric against longitudinal slipping when the use of the yarn is begun or discontinued without splicing to another yarn and to fabric having this characteristic. The method is shown as performed upon a circular, independent needle, knitting machine of the Banner type but it can be carried out as well upon other types of circular knitting machines.

When a yarn is substituted for another so that there is no break in the continuity of the knitting, it is customary to introduce new yarn a few needles before the old yarn is taken out. Consequently, the two yarns are overlapped or spliced and knitted into the fabric together for a distance which effectively locks the respective ends against longitudinal slipping. However, in certain types of knitting it happens that a yarn is taken out without being spliced to another yarn. In such case, the problem of preventing the end of the yarn from slipping longitudinally after it is cut is more difficult of solution. Two instances of this situation are shown in the accompanying drawing of which:

Fig. 1 is a diagrammatic illustration of plain three feed knitted fabric at the point at which the knitting of three yarns in alternation are discontinued and is succeeded by single feed knitting of a single yarn;

Fig. 2 is a similar view of a fragment of three feed split knit fabric in the area of the high splice in which one of the three yarns is spliced to another yarn for the high splice, the second of the three yarns is taken out and the knitting of the third of the three yarns is continued in the instep; and

Fig. 3 is a similar view of single feed fabric to which an additional separately fed and knitting yarn is added to change to two feed knitting.

As shown in Fig. 1, the fabric is knit of yarns 1, 2 and 3 knitted in rotation to form typical three feed fabric. In course 4, yarn 2 is taken out. The last loop to be knit by yarn 2 in this course is indicated at 5. Thereafter, yarn 2 is taken by every other needle only as indicated at 6 and 7 in such a way that the usual inlaid construction is produced. In consequence, after the yarn is cut its end is held by successive sinker loops and this is effective to prevent or, at least, limit its longitudinal slipping so that it cannot slip back to the wale represented by loop 5 to

2

cause a dropped stitch during pre-boarding or other finishing operations or subsequent use.

Heretofore it has been the practice to feed a yarn such as 2 which is to be discontinued to three or more consecutive needles beyond the last needle which knits it into the fabric, the three or more needles referred to being raised above the other sufficiently to clear their latches. This has proved ineffective because the end of 10 yarn 2 is then held only by a single loop and this is an insufficient anchorage against slipping. A further objection to this method of attempting to anchor the end of a discontinued yarn is that in certain methods of knitting it tends to break 15 the yarn particularly if it is very sheer such as the nylon customarily used in ladies' hosiery. By the method of this invention not only is the anchorage of the end of the yarn secure but greater latitude for self-adjustment of the yarn 20 is provided so that breakage is wholly eliminated.

In Fig. 1 yarn 3 is also shown as removed in course 8 the last loop of the fabric into which it is knitted being indicated by 9. Thereafter yarn 3 is taken by alternate needles and, as 25 before, is inlaid in the manner previously described respecting yarn 2 also as shown at 6 and 7. Thereafter the end of yarn 3 may be severed without endangering the fabric since it is securely anchored by the successive sinker 30 wales as already explained. Then the knitting of yarn 1 is continued the fabric now being single feed fabric knit of yarn 1 alone, yarns 2 and 3 having been taken out.

The fabric of Fig. 2 also illustrates a three feed fabric composed of yarns 10 and 11 and 12 35 knitted in rotation in the usual way. Yarn 10 is taken out as shown at 13 and yarn 14 substituted therefor. Yarn 14 is introduced at 15 and is knit together with yarn 10 for three 40 needles so that the two yarns are spliced in the usual manner. As already stated, no problem of yarn slippage arises since the yarns are spliced. Fig. 2 also shows that the knitting of yarn 11 45 is discontinued at wale 16 without being spliced to another yarn. Consequently, its end must be secured to prevent excessive longitudinal slipping and this is done by feeding the yarn to the needles knitting alternate wales 17—20 in the usual manner for inlaying a yarn in knitted 50 fabric. In other words, the procedure is the same as that described in respect to Fig. 1. Yarn 14 may be assumed to be that which knits the high splice of a stocking and since the fabric is split fabric the knitting of yarn 12 may be 55 considered as the instep yarn, the contiguous

edges of the two sections being interknitted to form a suitable suture.

The fabric of Fig. 3 is assumed to include a section knit of a single yarn 21 at the end of which a second yarn 22 is introduced and two feed knitting begun. The free end of yarn 22 is anchored against longitudinal displacement by feeding it to a few alternate needles such as 23 and 24 ahead of the first needle 25 which will actually knit it and so manipulating the needles that it is inlaid in consecutive sinker wales ahead of the first knitted wale. 10

Although the number of additional needles to which the yarn may be fed for the purpose of locking its end is shown as two in Figs. 1 and 3 15 and as three in Fig. 2, any number of alternate needles may be used to obtain an end inlay of the desired length.

The method of this invention is useful not only whenever the knitting of a yarn is discontinued 20 without splicing it to another yarn but also whenever a yarn is introduced without splicing. The only difference is that in the latter case the inlay occurs ahead of the actual knitting of the yarn whereas in the former it occurs after the actual 25 knitting is discontinued.

Another incidental feature of this invention is that the inlaid yarn is effective to conceal an eyelet which may result from the discontinuance of a yarn or from a change in the direction of 30 knitting. Since it is securely held it will bridge

any small opening which lies in its path. This is not likely to be so with the other method described herein because of the great probability that the yarn will slip from its anchorage and be entirely free up to the first loop at which it is actually knitted.

I claim:

A knitted fabric having a section composed of a plurality of yarns knitted in rotation and a succeeding section in which only one of said yarns is knitted, the exit end of each of the other yarns being inlaid in a plurality of consecutive sinker wales in the first course of said succeeding section.

EUGENE ST. PIERRE.
